UNITED STATES PATENT OFFICE.

JOHN H. WHALER, OF CANTON, OHIO.

DOOR-OPERATING DEVICE.

Application filed November 9, 1920. Serial No. 422,910.

To all whom it may concern:

Be it known that I, JOHN H. WHALER, a citizen of the United States, residing at Canton, in the county of Stark and State 5 of Ohio, have invented a new and useful Door-Operating Device, of which the following is a specification.

This invention relates to mechanism for opening and closing doors of the type commonly used on barns, garages and the like, in which a pair of doors is employed, one door being hinged at each side to the door casing, the said doors each swinging toward the center of the door aperture.

15 The main object of the invention is to produce a mechanism that will cause both of the doors to open and close simultaneously when either of them is swung.

Another object is the provision of means 20 for locking the doors in fully opened or closed position, so that they cannot be blown shut by the wind or caused to close in any other accidental manner.

A still further object is the provision of 25 means for closing the doors from a predetermined point outside of the building, so that the driver of an automobile or the like upon emerging from the building, may operate the mechanism to close the doors without alighting from the vehicle.

With these and other objects in view, the invention consists in the novel construction and arrangement of parts, hereinafter described, illustrated in the accompanying 35 drawings, and particularly pointed out in the appended claim, it being understood that various changes in the form, proportions, size and minor details of construction may be made within the scope of the 40 appended claim, without departing from the spirit or sacrificing any of the advantages of the invention.

In the drawings, Fig. 1 is a plan view of 45 my device with the doors shown in closed position in full lines, and with the mechanism and doors shown in dotted lines with the doors opened.

Fig. 2 is a longitudinal sectional view of 50 my device, shown attached to the roof beams and doors of a garage or like structure.

Fig. 3 is a detail perspective view of a

section of the track with the sliding carriage shown in position thereon;

Fig. 4 is a fragmentary view showing a bottom plan of a section of the track with 55 the carriage in position thereon.

Fig. 5 is an enlarged detail of the latch mechanism.

Fig. 6, is a section on the line 6—6 of 60 Fig. 5.

Similar numerals of reference indicate corresponding parts throughout the several figures of the drawing.

At 1, I have shown the front wall of a barn, garage or similar structure, the said 65 wall being provided with a doorway designed to be closed by doors 2 and 3 which are hinged to opposite sides of the said doorway. Secured in approximate horizontal alinement with the top of the doors 2 70 and 3, is a track indicated at 4, which track is composed of a pair of angle irons, arranged with their vertical portions facing each other, in spaced relation. This track will be secured to any suitable portion of 75 the structure, as for instance the beams 5 which support the roof of the building. The track 4 will be placed as shown in Fig. 1, in direct alinement with the abutting inner edges of the doors 2 and 3 and will extend 80 rearwardly at right angles to the said doors, to a point within the said garage.

Mounted to slide upon the track 4, is a carriage 6, which is formed by stamping a piece of sheet metal with lateral corner 85 projections and bending the said projections upwardly and inwardly as clearly shown at 7 in Fig. 3, so that the said portions 7 engage the horizontal flanges of the L-shaped members composing the track. 90 Pivotedly secured to the under side of the carriage 6, at a point slightly to the rear of the forward edge of the said carriage, is a cross arm indicated at 8, which cross arm is provided with apertures 90 near 95 either of its extremities.

At 10 is shown a pair of rods, each of which carries upon one end a hook portion 11, each of which hook portions is inserted through one of the apertures 9 in the cross 100 arm 8. Upon each of the opposite ends of the rods 10 is formed a second and similar

hook indicated at 12, the said hook 12 engaging eye members 13 and 14, which eye members are carried by the doors 2 and 3 respectively. At the rear end of the carriage 6 is a central aperture shown at 15, through which aperture is secured one end of a cable 16 which cable extends rearwardly and over a pulley 17, and has secured upon its rear extremity a weight 18, the purpose of which will be hereinafter set out.

Pivotaly mounted between the vertical portions of the L-shaped members of the track 4, is a latch member indicated at 19. The rear or lower end of the latch member is arranged to engage the rear end of the carriage member 6 when the said carriage member is advanced to its extreme forward position and both of the doors are thrown completely open as indicated by the dotted lines in Fig. 1. The pivotal point of the latch member 19 will be nearer the front extremity of the said latch member than the rear thereof, the said latch therefore having a continuous tendency to drop at the rear end. A member 20, which is of substantially inverted U shape in cross section, and having a slot shown at 21 in either of its side portions, is secured upon the track 4 by a rivet, bolt or the like indicated at 22, the said bolt being the pivot of the latch member 19.

An eye 23 is formed at the forward extremity of the member 20 and through the said eye is secured one end of the cable 24 which cable passes forward and through the front wall of the garage, terminating at a point outside of the garage, convenient to be reached by the driver from the seat of an automobile leaving the garage. Secured to the rear end of the member 20 is one end of a coil spring 26, the opposite end of which will be attached to a stud, bolt or the like secured to the track 4. It will be obvious from the foregoing that a pull exerted upon the outer end of the cable 24, through its attachment to the eye 23 carried by the sliding member 20, will pull the said sliding member forwardly and cause it to ride over the upwardly projecting front end of the latch member 19, which will obviously depress the said front end of the latch member, consequently causing its lower or rear end to be raised. When the pull upon the cable 24 is released, it is obvious that the coil spring 26 will return the sliding member 20 to its rear position and allow the lower end of the latch member 19 to once more drop.

Referring to Figures 3 and 4, it will be seen that I employ a coil spring shown at 27, which coil spring is attached at one end to the carriage 6, and at its opposite end to the end of the cross member 8 which carries the rod 10 engaging the door 2, which door it

will be seen by reference to Fig. 1, must close ahead of the door 3 in order that the sealing strip 28 carried by the door 3 will close properly upon the outside of the door 2.

In operation we will assume that the doors of the garage are closed and locked. The lock may be arranged to be operated from either the outside or inside of the garage. Assuming that the doors are unlocked from the outside, the door 3 will be swung open exerting a pull upon the rod 10 attached thereto, which pull being transmitted through the cross arm 8 to the carriage 6, will cause the said carriage to slide forward upon the track 4. It is obvious that the advancement of the carriage 6 will cause the rod 10 attached to the door 2, to swing the said door 2 open simultaneously with the opening of the door 3. When the doors have reached the dotted line position indicated in Fig. 1, the carriage 6 will have advanced to its extreme forward position, and in doing so will have lifted the rear end of the latch 19 and passed beneath the said latch allowing it to drop just as the said carriage reaches the limit of its forward movement. It will be obvious that the latch in dropping behind the carriage 6 will prevent the counter weight 18 through its attachment to the rear end of the carriage by the cable 16, from returning the said carriage to its rearward position on the track and closing the doors. When, however, the automobile has been driven from the garage, the operator of the said machine by exerting a pull upon the outer end of the cable 24 will slide the member 20 forward and over the upwardly projecting front end of the latch, causing its rear or lower end to be lifted out of the path of the sliding carriage as previously described, and allowing the counter weight 18 to draw the said carriage rearwardly on the track and swing the doors shut. The coil spring 27, by exerting a slight pull upon the end of the cross arm which is attached by the rod 10 to the door 2, will swing the said cross arm, causing the door 2 to close slightly in advance of the door 3.

It will be obvious that by reversing the latch used for locking the doors open, a duplicate thereof may be employed to lock the doors in closed position.

Having now described my invention what I claim as new and desire to cover by Letters Patent is:—

In a door operating device; a pair of spaced, horizontally disposed, parallel angle members forming a track, a carriage slidably mounted on said track, a cross arm pivoted to the under side of said carriage and having its ends extended on either side beyond said carriage, a rod pivotally secured in each of said extended ends and connected to one of the doors designed to be operated, the

said carriage being arranged to slide upon said track when either door is moved and to move the other door simultaneously, a latch pivoted between said spaced angle members 5 and arranged to engage said carriage when the said doors are fully opened, a U-shaped member fitting over said angle members and adjacent said latch, a cable attached to said U-shaped member whereby said U-shaped member may be moved forwardly and into 10 position to raise said latch and release said carriage, and a weight operatively connected to said carriage whereby said carriage is moved rearwardly and said doors closed when said carriage is released by said latch. 15

In testimony that I claim the above, I have hereunto subscribed my name.

JOHN H. WHALER.
